UNITED STATES PATENT OFFICE.

WILLIAM G. POWELL, OF ALTOONA, PENNSYLVANIA.

AUXILIARY DOOR FOR FREIGHT CARS.

Application filed August 29, 1924. Serial No. 735,013.

This invention relates to doors and more particularly to auxiliary doors for use on freight cars, in order to provide an additional width of opening to facilitate the loading of large objects, such as automobiles, into the cars.

It is an object of this invention to provide a novel and improved type of auxiliary car door.

10 More particularly it is an object of this invention to provide a novel and improved auxiliary door which rolls in the same plane as the main door but in an opposite direction, the abutting edges of the two doors being weather-tight when closed and offering no obstructions to loading when open.

Another object of this invention consists in the provision of an auxiliary car door having means at both vertical edges thereof 20 for tightly wedging it in a closed position and locking it in this position from the inside of the car.

Still another object of this invention consists in the provision of an auxiliary door for 25 freight cars, having means whereby a temporary lining can be secured thereto when the auxiliary door is not in use in order to adapt the car for the carrying of grain, etc.

A further object of this invention consists 30 in the form of an auxiliary car door having certain novel and improved features which will be more clearly described in the following specification and thereafter claimed.

For an understanding of this invention, 35 reference should be had to the following specification taken in conjunction with the accompanying drawings, wherein is disclosed one embodiment of the invention, with the understanding that various modifications 40 may be made therein without departing from the scope of the attached claims.

In said drawings:

Figure 1 is a side elevation of the door portion of a box car showing on the right the usual sliding door and on the left the auxiliary door;

Figure 2 is a vertical section on an enlarged scale taken on the line 2-2 of Figure 1;

50 Figure 3 is a horizontal section on an enlarged scale taken on line 3-3 of Figure 1;

Figure 4 is a partial vertical section on line 4-4 of Figure 1;

55 Figure 5 is a partial horizontal section on line 5-5 of Figure 1;

Figure 6 is a partial horizontal section on line 6-6 of Figure 1;

Figure 7 is a section on line 7-7 of Figure 3 looking in the direction of the arrow, and

Figure 8 is an elevation of a detail of the locking means for the auxiliary door.

When using box cars for the transportation of large objects of freight, such as automobiles or other types of machinery, it is found difficult to load them through the usual door in the side of the car, and it has been proposed to provide an additional or auxiliary door which may be used at such times as necessary in order to provide an enlarged opening to facilitate the loading. Various difficulties have been met in the design of such a door, and the present invention contemplates a number of improvements, such as will be apparent upon reading the accompanying specification and which will be particularly pointed out in the claims.

Referring to Figure 1, it will be noted that on the right of the figure is illustrated an ordinary box car door 10 adapted to slide to the right to provide an opening through which the car may be loaded. At 11 is shown an auxiliary door somewhat similarly constructed and adapted to slide to the left to enlarge the opening provided by the moving of the door 10. When it is not desired to use the auxiliary door, means is provided on the inside thereof, for rigidly securing it in position and wedging it against moving or rattling.

While any ordinary construction of door 90 may be used, it is preferred to use the particular construction illustrated and described in my co-pending application, Serial No. 725,653, side doors, filed July 12, 1924. In this application, there is described a form 95 of side door for cars formed of three sheet metal panels, such as 12, 13 and 14, struck up at the meeting edges and there riveted together in a plane parallel to the main part of the panel but outwardly thereof to form 100 transverse reinforcing corrugations in the door as shown at 15 and 16. The rear edge of the door is composed of a vertical angle bar 17 riveted to the right angle flanged portion 18 of the panel plates at 19, and at 105 20 to the tops of the corrugations 15 and 16. The rear edge of this angle bar is distorted inwardly as shown at 21 in order to form a weather strip, cooperating with the distorted Z-bar 22 which forms a reinforcement, 110

bolted in two directions, to the door frame post 23. At 24 is shown the sheet-metal side of the car secured to the web of the Z-bar 22 by means of the bolts 25. Secured to the inner face of the door frame post 23 is the car lining 26, usually formed of wood, which adapts the car for use in the carrying of grain and similar articles.

Reference to Figure 3 shows that the rear 10 or trailing edge of the auxiliary door 11 is constructed in exactly the same manner as the trailing edge just described for the main door 10, the reference characters in this instance being primed, it of course being understood that the panels 12', 13' and 14' of the auxiliary door are constructed in a similar manner to those of the main door.

In the drawings, the doors are illustrated as rolling upon a track at the bottom, but 20 it is to be understood that this invention is equally applicable to top hung doors. The bottom edge of the lower panel of each door is not flanged but is merely a straight continuation of the main portion of the panel 25 and is reinforced by the Z-bar 27, having its upper flange 28 securely riveted to the inner face of the panel with the lower face of the web in line with the lower edge of the panel and extending inwardly therefrom so 30 that the lower flange 29 of the Z-bar forms in effect an inwardly offset, guide flange preventing the door from moving outwardly by its cooperation with the inner face of the door track 30. This track may conveniently 35 be a channel member arranged with the web uppermost and supported from the longitudinal beams 31 beneath the car by means of the cast or pressed brackets 32. It is spaced a slight distance from these 40 beams in order to provide clearance for the flange 29 of the lower stiffening members of the doors.

As clearly shown in Figures 1 and 2, the doors are supported by the rollers 33, one 45 at each of the lower corners thereof, which rollers are adapted to run upon the track 30, and are mounted for rotation in castings 34 which are securely riveted to the lower corners of the panels, the upper flange 28 50 of the lower stiffener 27, and the webs of the vertical edge stiffeners.

The upper edges of the panels 12 and 12' are reinforced by Z-bars such as 35, best 55 shown in Figures 2 and 4, the upper flange 36 of which is securely riveted to the outer face of the flat portion of this panel. The upper edge of this panel together with its reinforcing Z-bar serves, as will later be described, to retain the door against falling 60 away from the car, and in order that the upper edge may be stiffened against bending about a horizontal axis, means are provided for attaching the opposite flange 37 of the Z-bar to the panel. For this purpose, the 65 material of the panel is pressed outwardly

to form the short vertical corrugations 38, the summits of which are securely riveted to the flange 37, the material to form these corrugations being provided by allowing the upper edge of the panel to draw downwards 70 to a position shown at 39 in Figure 4, which best illustrates this construction.

The upper edges of the doors are guided and prevented from lifting by means of the Z-bar 40, the upper flange 41 of which is 75 securely riveted to the car roofing member 42, and the lower flange 42' of which overhangs the upper vertical flange 36 of the top stiffener of the door, thus serving to divert water to the outside of the door and 80 to maintain the upper edge of the door against falling away from the car. At the same time, this Z-bar prevents any lifting of the door which might disengage the depending flange 29 from the channel between 85 the track 30 and the car beam 31, thereby insuring that the door always remains in the proper position.

Thus far, the construction of the two doors has been identical in every way, except that 90 the auxiliary door is narrower than the main door, but the meeting stiles of the two doors are materially different. The reinforcing member forming the meeting stile 95 of the main door is a Z-bar having its web 43 riveted to the outturned flanges 44 of the door panels in a similar manner to that in which the angle 17 is fastened to the flanges 18. The flange 45 is riveted to the summits 100 of the two transverse reinforcing corrugations at the meeting edges of the panels as shown at 46, and the remaining flange 47 of the Z-bar is curved as shown in Figure 3 so that it extends substantially at an angle 105 of 45° to the web. By attaching the webs 17 and 43 in the manner described, it will be noted that they are each riveted to the door in two planes at right angles to each other, thus effectually preventing rotation of these stiffeners about a vertical axis. 110

The meeting stile of the auxiliary door comprises the large shallow channel bar 48 having its back riveted to the outturned flanges 49 of the door panels so that the outer edge of the outer flange is flush with 115 the face of the flange 45 of the vertical stiffener on the main door, the end 49 of this flange abutting against the face of the web 43 to form a weather-tight joint assisted by the curved flange 47 of the vertical stiffener 120 on the main door. In order to prevent the channel bar 48 rotating about a vertical axis, due to the strains of closing and shifting freight within the car, it is securely riveted to the under side of the summits of the 125 two transverse reinforcing corrugations by means of the angle brackets 50 having the strengthening webs 51. Each of these brackets has at its inner end the flange 52, 130 the inner face of which is in the same plane 135

with the inner face of the flange 53 of the channel member 48. The surface thus formed by these two flanges is abutted by the wooden facing piece 54, which is securely fastened thereto by the bolts 55.

The meeting stile of the auxiliary door must be held in a rigid position when the door is closed in order to provide means for fastening the main door, and for this purpose, there are provided wedging means at both the top and bottom of the meeting stile. The channel member 48 extends only to the surface of the floor of the car with sufficient clearance to allow for easy sliding, whereas the track 30 is a material distance below the edge of the surface of the floor, as best shown in Figure 2. The casting 34 which houses the roller provides rigid means for connecting this vertical stile member and the lower horizontal edge stiffener. A portion of this casting is cut away as shown at 56 in Fig. 1 and is provided at the rear thereof with the inclined surface 57, best shown in Figure 6, which is adapted to 25 wedge behind the spud 58 fastened to the track 30 and having the corresponding inclined face 59, thereby serving not only to limit the movement of the door in its closing direction but also to securely press it inward against the edge 60 of the car floor reinforcing member to maintain the door both weather-tight and against rattling. The flanges 45 and 47 of the vertical stiffener 43 of the main door are clipped at the 30 bottom as shown in Figures 1 and 6 in order to make room for the roller casting and to give clearance to the spud 58 and the inclined portion of the casting on the auxiliary door.

In a similar manner, the upper edge of the door is adapted to cooperate with the double wedge member 61, as shown in Figure 5, which member is secured in the offset portion 62 of the Z-bar 40 which maintains the door in position on the car. It will be seen that the upper flange 36 of the Z-bar 35 which forms the top reinforcing member for the door is extended so that it will ride up on the inclined surface 63 of this wedge member and perform the same function as the spud 58 in pressing the door inward against the guide strip 64.

In order to maintain the auxiliary door tightly closed and pressed against the wedges at its forward end and also drawn tightly against the parts 60 and 64 at the rear edge, a latch is provided which has a wedging action in two directions, that is, toward the direction of closing the door and which also draws the door inward toward the body of the car. It is preferable to have this latch on the inside of the car so that when it is once locked there is only need of one lock and seal on the outside of the meeting edges of the two doors. This latch in-

cludes a double wedge member 65 riveted near the rear edge of the door in the hollow formed on the inside between two of the panels of the door, as shown best in Figures 2 and 3, and a double cam member rotatable 70 about a pivot secured upon a base 66 riveted to the flange end web '22' of the distorted Z-bar which reinforces the edge of the opening in the car door.

As best shown in Figure 7, the base 66 is 75 provided with a pivot stud 67 upon which is mounted the double cam member 68 held thereon by means of the nut 69 and the interposed washers 70. This cam member is provided with an operating handle 71 and 80 has the internal eccentric cam face 72 adapted to cooperate with the lug 73 formed on the part 65 to draw the door inwardly toward the car as the handle 71 is rotated from a position to the right of that shown 85 in Figure 7 and somewhat above the horizontal. At the same time, the edge 74 of the cam member 68 increases in height from the end 75 to the end 76 and is adapted to cooperate with the inclined face 77 on the 90 portion 65, in order to force the door toward its closing position at the same time that it draws it inward due to the rotation of the handle 71. The action of this double cam latch will be obvious from an inspection of 95 Figures 3, 7 and 8, and it will be clear that when the door is in its locked position the handle 71 will be substantially vertically downward and out of the way.

To provide for the use of cars having this 100 form of door for other purposes than the hauling of automobiles and such large pieces of machinery, means is provided for extending the normal wooden lining 26, 26' of the car over the inside of the auxiliary door, 105 thus allowing for the carrying of grain, etc. For this purpose, the temporary lining 78 is provided which may be fastened, by any suitable means, between the door post 23' and the facing piece 54 carried by the channel bar 48 of the auxiliary door. A strip 79 is provided at the edge of this temporary lining 78 in order to bring it out into the same plane with the molding 80 which holds the lining 26 to the post 23 in order that 110 standard grain doors 81 may be used the same as in ordinary box cars, thus in effect making a double purpose car.

Any suitable form of latch or hasp mechanism such as 82 may be used whereby the 115 main door may be secured to the edge of the auxiliary door in the same manner that it would be secured normally to the siding of the car in the absence of the auxiliary door.

From the above description, it will be evident that this invention provides a novel and improved door system for use on freight cars, adopting them for use in the loading of large articles of freight, such as 120 125 130

machinery and automobiles, and also allowing the use of the car in the normal manner for the carrying of grain and other small articles, no obstructions being applied near the meeting edges of the two doors for the purpose of fastening either door in its closed position. The use of such obstructions is objectionable and they are usually short lived due to their being struck while loading the car. The auxiliary door in addition has the full height of the main door, and is in every respect the same and equally as strong. While but one embodiment of this invention has been disclosed in the accompanying drawings, it is to be understood that various modifications and arrangements of parts may be made without departing from the spirit of the invention as expressed in the following claims.

Having thus described my invention what I claim as new and desire to secure by Letters Patent is:

1. An auxiliary door for freight cars including in combination with a door frame, door panels adapted to overlay said frame when the door is closed, reinforcing means at the top and bottom thereof, rollers on which said door is adapted to slide, and cam means secured to the door frame acting in two directions to lock said door against rattling, said means engaging a part on said door remote from the edge thereof and outside of the plane of the panels thereof.
2. An auxiliary door for freight cars including in combination, door panels, reinforcing members at the top and bottom thereof, slideways to retain said door in position and wedging means cooperating with portions of said door to hold the forward edge of said door against rattling when closed, one of the said wedging means being below the level of the car floor and secured to said slideway.
3. A door system for freight cars including in combination, a door frame, a main sliding door, an auxiliary sliding door, said doors being in the same plane and abutting when closed to cover said frame, a weather-tight joint at said meeting edges and channel reinforcing means on said auxiliary door to form a frame member for

said main door and means thereon for mounting a temporary lining when said auxiliary door is not in use.

4. A door system for freight cars including in combination, a door frame, a main sliding door, an auxiliary door sliding in the same plane as said main door, meeting stiles on said doors forming a weather-tight joint, the stile on said auxiliary door being a channel member having the plane of its web at right angles to the plane of the doors and means extending beyond the outer face of the door for preventing rotation of said channel about a vertical axis.

5. A door system for freight cars including in combination, a door frame, a main sliding door, an auxiliary door adapted to slide in the same plane as the main door and to abut the same, a channel member secured to the meeting edge of said auxiliary door with its channel facing the meeting edge of the main door, a reinforcing member including a weather strip secured to the meeting edge of said main door, the outer flange of said channel being adapted to overlap said weather strip.

6. The combination with a car body having a floor and door opening, of a door comprising two complemental sections arranged to slide in the same plane but in opposite directions to open and close said door opening, a track below the level of the floor, means cooperating with one of said sections to individually wedge the vertical edges thereof against said car when said door is closed, and means on said track below said floor to wedge the bottom edge of one section against the edge of said floor.

7. The combination with a car body having a door opening, of a framed door comprising two complemental sections arranged to slide in the same plane but in opposite directions to open and close said door opening, means cooperating with one of said sections to individually wedge the vertical edges thereof against said car when said door is closed, and means on said frame to force said section toward said other section.

In testimony whereof I hereunto affix my signature.

WILLIAM G. POWELL.
